UNIVERSAL JOINT AND RATCHET DEVICE

Denis Grand Maison, Markstay, Ontario, Canada

Application December 8, 1943, Serial No. 513,434

2 Claims. (Cl. 192—43.2)

This invention relates to an improved universal joint and ratchet device adapted to be interposed between the handle and work-engaging member of a socket wrench or like tool, whereby said tool may be efficiently applied and operated where access to the work is difficult or continuous rotation of the work-engaging member is impossible.

The primary object of the present invention is to provide a device of the above kind embodying means whereby the work-engaging member may be selectively driven in either direction with a ratchet action, or whereby the work-engaging member may be positively and continuously driven in either direction without a ratchet action.

A further object is to provide a device of the above kind which is durable, efficient in operation and otherwise well adapted for a successful commercial use.

The present invention consists in the novel form, combination and arrangement of parts hereinafter more fully described, shown in the accompanying drawings and claimed.

In the drawings, wherein like reference characters indicate corresponding parts throughout the several views:

Figure 1 is an elevational view of a socket wrench equipped with a universal joint and ratchet device constructed in accordance with the present invention.

Figure 2 is an enlarged elevational view of the universal joint and ratchet device per se.

Figure 3 is a top plan view of the device shown in Figure 2.

Figure 4 is a horizontal section taken on line 4—4 of Figure 2.

Figure 5 is a bottom plan view of the upper casing section and associated parts of the device, with the ratchet ring operatively associated therewith.

Figure 6 is a view similar to Figure 5 with the ratchet ring removed.

Figure 7 is a top plan view of the lower casing section of the device, showing the pawl carried thereby.

Figure 8 is an elevational view of the cover plate for the casing, together with the associated pawl-shifting device.

Figure 9 is a bottom plan view of the construction shown in Figure 8.

Figure 10 is an elevational view of the ratchet ring and the associated universal joint member.

Figure 11 is a bottom plan view of the element shown in Figure 10.

Figure 12 is an enlarged perspective view of the shifting lever for the pawl carried by the upper casing section.

Figure 13 is an enlarged perspective view of the upper yoke member of the universal joint.

Referring in detail to the drawings, the present device has been shown by way of example as applied to or incorporated in the structure of an extension socket wrench including a brace-like handle 5 and a shank extension 6 having a work-engaging socket 7 on the lower end thereof. The device is illustrated as interposed between the shank of the handle 5 and the shank extension 6, and it includes a casing composed of upper and lower ring sections 8 and 9 interlocked against relative rotation, as at 10, and held together by screws 11 passing through openings 12 of the upper section 8 and having threaded engagement in opening 13 in the lower section 9. 15 Rotatable in the casing is a ratchet ring 14 having smooth end portions rotatably fitting in the central openings of said casing sections 8 and 9 and having intermediate its ends a pair of spaced integral ratchet wheels 15 and 16 whose teeth respectively face in opposite directions. The intermediate portion comprising the ratchet wheels 15 and 16 is received within mating annular rabbets 17 and 18 provided in the inner peripheries of the adjacent faces of said casing sections 20 8 and 9. A recess 19 is provided in the under surface of the casing section 8, within which is arranged a pawl 20 disposed to engage the upper ratchet wheel 15 of ratchet ring 14. The pawl 20 is yieldingly urged into engagement with the ratchet wheel 15 by means of springs 21 and 22. A pawl-releasing lever 23 has a shaft 24 journaled in the section 8, and provided on the shaft 24 directly above the pawl 20 is an arm 25 carrying a crank pin 26 engaged in a longitudinal slot 27 of said pawl 20. The lever 23 is normally disposed to extend inwardly toward the center of section 8, and outward swinging of the lever 23 will effect outward movement or retraction of the pawl 20 from engagement with 25 the ratchet wheel 15.

Another lever 28 has a shaft 29 journaled in the casing section 8 and an arm 30 is provided on the lower end of the shaft 29 within a recess 31 of said section 8, said arm 30 being provided 35 with a depending crank pin 32. The casing section 9 also has a relatively deep recess 33 in its upper face within which is disposed a pawl 34 arranged to engage the lower ratchet wheel 16 of the ratchet ring 14 and normally urged into 40 engagement with the latter by means of springs 35 50 55

35 and 36. The crank pin 32 of the lever 28 engages in a longitudinal slot 37 of the pawl 34, and the lever 28 normally extends inwardly toward the center of the casing section 8 and is operable by outward swinging movement thereof to retract or disengage the pawl 34 from the ratchet wheel 16. It will be noted that the pawls 20 and 34 face in opposite directions to correspond with the ratchet wheels 15 and 16, one pawl acting to prevent rotation of the ratchet ring 14 in one direction, and the other pawl acting to prevent its rotation in the opposite direction. Naturally, when both pawls are engaged with the ratchet ring 14, it will be caused to rotate with the casing regardless of which direction of rotation is imparted to said casing.

The casing has a top cover plate 38 in which is journaled a shaft 39 of a pawl-retracting device including an arm 40 extending between the inner ends of the levers 23 and 28 and provided with an upturned free end 41 provided with a reduced terminal end portion adapted to selectively enter one of an arcuate series of openings 42 provided in the cover plate 38, when registered therewith. The pawl-retracting device further includes a handle 43 fixed on the upper end of the shaft 39, and a spring 44 is interposed between the handle 43 and the cover plate 38 to yieldingly elevate the arm 40 and engage its reduced terminal in the opening 42 with which it may be aligned. By pressing downwardly on the handle 43, the terminal of the arm 40 may be disengaged from an opening 42 to permit swinging of said arm in the desired direction for actuating either one of the levers 23 or 28. Thus, by swinging the arm 40 in one direction, the lever 23 may be swung outwardly to release the associated pawl 20, while the pawl 34 remains active. This affords a ratchet drive between the handle 5 and the work-engaging member 7 in one direction, and a reverse ratchet drive may obviously be provided by causing the arm 40 to swing the lever 28 outwardly and retract the pawl 34 while allowing the pawl 20 to remain operative. The terminal of the arm 40 will engage in an opening 42 when in position to hold either lever 23 or 28 inoperative, and, in the intermediate position of the arm 40, levers 23 and 28 are allowed to swing inwardly so that both pawls become operative and a positive, continuous driving connection is provided in either direction between the handle and the work-engaging member of the tool.

The present device further includes a yoke or bail 45 straddling and having its legs pivoted to opposite sides of the upper casing section 8, as at 45, within relatively wider recesses 47 provided in said casing section 8. The yoke 45 has an intermediate socket member 48 whose polygonal socket is adapted to receive a corresponding plug on the end of the shank of the handle 5. Further, the ratchet ring 14 has a pair of diametrically opposed spaced bearings 49 in which are journaled the ends of a shaft or pivot pin 50 carrying a depending plug member 51 on the intermediate portion thereof. The plug member 51 is adapted to be received in the polygonal socket 52 on the upper end of extension shank 6 of the tool, and any well known provision may be made for detachably retaining the plug of the shank 6 of handle 5 in the socket 48 and for retaining the plug 51 in the socket 52. It will be apparent

that by reason of the pivotal connection of the yoke 45 with the casing 8, 9 and the pivotal mounting of plug 51 with respect to ratchet ring 14, a universal joint is had between the handle 5 and the shank 6, when the pivots of plug member 51 are disposed at a right angle to those of yoke 45, so that they may assume relative angular positions while rotating the work.

From the foregoing description, it is believed that the construction and operation, as well as the advantages of the present invention, will be readily understood and appreciated by those skilled in the art. The present device affords a reversible ratchet drive incorporated in a universal joint adapted for coupling shank members of a wrench or like tool. The device further embodies provision whereby either one of a pair of oppositely acting pawls may be rendered inoperative so that a ratchet drive may be had in either direction, and whereby both of said pawls may be permitted to remain in operative position for providing a continuous, positive drive in either direction between the handle and the work-engaging element of a tool. Minor changes in the details of construction illustrated and described are contemplated, such as fall within the spirit and scope of the invention as claimed.

What I claim as new is:

1. In a wrench or like tool, a universal joint and ratchet device comprising a casing, a ratchet ring journaled in the casing for relative rotation therein, said ratchet ring having a pair of oppositely facing ratchet wheels in fixed relation thereto, oppositely acting spring-pressed pawls carried by the casing and normally engaging the respective ratchet wheels, means carried by the casing and manually operable to render and retain either desired one of said pawls inoperative, a yoke pivoted to the top of said casing and having a driving socket adapted for reception of the shank of a handle, and a plug member depending from and pivoted to the ratchet ring for swinging movement about an axis diametrically of said ring, said plug member being adapted for driving reception within a socket of a tool shank provided with a work-engaging member, said ratchet ring being rotatable to position the pivotal axis of the plug at a right angle to that of the yoke so as to afford a universal joint between the handle and the tool.

2. In a device of the character described, a casing, a ratchet ring journaled in the casing for rotation relative thereto, a pair of oppositely facing ratchet wheels carried by the ratchet ring in fixed relation to the latter, oppositely acting spring-engaged pawls carried by the casing and arranged to engage the respective ratchet wheels, manually operable means carried by the casing for selectively rendering and retaining either desired one of said pawls in retracted inoperative position with respect to its associated ratchet wheel, and means to connect opposite ends of the casing and the ratchet ring with tool shank sections, said last-named means embodying universal joint elements pivoted respectively to the casing and to the ratchet ring, said ratchet ring being rotatable to position the pivotal axes of said universal joint elements at an angle to each other and afford a universal joint between the tool shank sections.

DENIS GRAND MAISON.
